UNITED STATES PATENT OFFICE.

ALBERT N. LYBERGER, OF ELYRIA, OHIO.

CAR REPLACER.

1,418,588.

Specification of Letters Patent. Patented June 6, 1922.

Application filed July 19, 1921. Serial No. 485,866.

To all whom it may concern:

Be it known that I, ALBERT N. LYBERGER, a citizen of the United States, residing at Elyria, in the county of Lorain and State 5 of Ohio, have invented a new and useful Car Replacer, of which the following is a specification.

This invention relates to car replacers, and is designed as an improvement upon the 10 structure shown in my Patent No. 1,294,926, dated Feb. 18, 1919.

The object is to provide means for placing derailed cars, etc., upon railway tracks, such means consisting of a pair of similarly 15 constructed metallic members capable of being easily carried to any position along the track where needed, and of being readily placed in position with relation to the wheels of the derailed car and the rails of the track, 20 to elevate the said wheels and force the same over and onto the tread of the rail, when power is applied to the car to draw the same forward.

Another object is to provide a pair of 25 such members, each formed of a stout hollow casting of suitable metal, reinforced on the interior thereof by strengthening ribs, and having means for engaging with the adjacent side of the rail so that the great 30 weight to which the members are subjected will be imparted to the said rail the moment the car wheel begins to ride upwardly along the member in a longitudinal direction.

A further object is to provide a pair of 35 car replacing members to be used, one between the rails and against the inner face of one rail and the other against the corresponding outer face of the other rail, the said members having means for locking 40 them to the rails, said locking means being adjustable to adapt the members to rails of different sizes and dimensions, and having further means for entering between the ties of the track to prevent any material longitudinal movement of the replacers along the 45 track when the wheel is being dragged up and along the same, in the event the locking means might slip.

A full and complete understanding of the 50 invention may be obtained from a consideration of the following detailed description, taken in connection with the accompanying drawings forming a part of this specification; it being understood that while the 55 drawings show a practical form of the in-

vention, the latter is not to be confined to strict conformity therewith, but may be changed or modified, so long as such changes or modifications mark no material departure from the salient features of the invention, 60 as specifically pointed out in the appended claims.

In the drawings, in which similar reference characters designate corresponding parts throughout the several figures— 65

Fig. 1 is a plan view of a portion of a railway track and showing, in full lines, the position of the replacing members located at the righthand side of their respective rails and, in dotted lines, the positions of the 70 members when located at the lefthand side of the rails;

Fig. 2 is an end view of the same, the rails being in section and the positions of the 75 members being illustrated in a similar manner;

Fig. 3 is a side elevation of the outside replacer, or that member used on the outside of either rail and showing its relation to the adjacent rail, the scale being somewhat enlarged; 80

Fig. 4 is an inverted plan view of the same member.

Fig. 5 is a further enlarged transverse section, through the inside replacer and the 85 adjacent rail and taken substantially on the line 5—5 of Figure 1.

Fig. 6 is a similar view of the outside member, taken substantially on the line 90 6—6 of Figure 1 and drawn on the same scale as Figure 5.

The car replacing members of the present invention consist of an inner member 1 and an outer member 2. Ordinarily derailed cars lie in a position with the wheels at one 95 side resting upon the ties adjacent to the inner side of one of the rails or the rail upon which said wheels formerly rested. For the purpose of replacing these wheels upon the track, the member known as the 100 "Inside" member is used. Necessarily the opposite wheels of the car assume a corresponding relation to its proper rail though upon the outside of the latter while resting upon the ties, and it is in connection with 105 these wheels that what is known as the "Outside" member is used.

The two members, as in the aforesaid patent, are similar in construction and consist of a hollow casting, formed of steel and 110

cast into an elongated member adapted to lie along the rails of the track, and each having a transversely disposed locking device adapted to engage the adjacent rail and having a wedging means for drawing the locking device tight to rigidly hold the replacing members against the rails and impart the weight of the shifting car to the latter.

The inside member 1 has an elongated body portion with a gradually upwardly inclined track surface or platform extending from each end and having its greatest height at the central point thereof, the apex being indicated at 3 and the top surface gradually increased in width towards each end 4, which end is rounded and lies substantially flush with the top surface of the ties 5, so that when the derailed wheel is drawn forwardly, as through the medium of a locomotive, the flange 6 of the wheel 7 (see Fig. 5) will readily mount upon the member 1 and rise to the apex 3 thereof.

The top face of the member 1 is provided with an upstanding deflecting guard flange 8 formed integrally therewith and starting at each end 4 at the corner remote from the rail 9, and extending entirely along the member, the latter being somewhat narrower at the center than at the ends, as clearly shown in Figure 1, where the said flange 8 is formed into a curved deflector 10 extending toward the said rail 9, and which is adapted to come into contact with the rising and forwardly moving flange 6 of the wheel 7 and to force the same over and toward the said rail. The apex 3 has a drop or fall 11 extending longitudinally of the member 1 and alongside the ball or head of the rail 9 and located considerably below the top surface of the same, so that the tread of the wheel may come to a rest upon the rail, while the flange 6 rides along in the longitudinally extending channel provided by the drop or fall 11.

The bottom of each end 4 of the member 1 is cut away or inclined adjacent to the rail, as indicated at 12, so that the major portion of the member rests upon the ties 5 and the inside base flange of the rail 9 projects beneath the cut-away portion 12 and receives the weight of the overlapping edge of said member in order to transmit the weight of the car to the flange of the rail, as will be readily understood upon reference to Figures 5 and 6 and thus prevent mutilating the ties and providing for continuously supporting the said member throughout its length.

The inner or rear wall 13 of the member 1 is adapted to rest directly upon the ties, and the outwardly-flaring end portions are each provided with a base flange 14 extending laterally and provided with a series of notches 15 for the reception of spikes which, when desired to reinforce the locking means about to be described, may be driven into

the ties 5 so as to prevent any transverse or longitudinal movement of the member, as will be clearly understood.

Extending from the wall 13 to the depending wall 16, which fits flat against the web of the rail, is a series of transverse, reinforcing ribs or webs 17 which add much to the strength of the member without materially increasing its weight, and the ends 4 are connected to the outermost web 17 by 75 a longitudinally disposed web 18 as shown in Figure 4.

The vertically disposed inner or rear wall 13 is provided, at a central point with an aperture 19 located at a point opposite the upper portion of the rail 9 for the passage of a transversely disposed locking bar 20, having an intermediate drop 21, and an extension 22 lying immediately beneath the base flange of the rail 9 and terminating in a hook 85 23, adapted to engage with the outer flange of the rail and prevent any inward movement of the locking bar.

The upper, inner portion of the bar 20, where passing through the aperture 19, is 90 provided with a vertical passageway 24 adjacent to the end thereof and crossing the inner face of the vertical wall 13 of the member 1. A tapered wedge or key 25 is located in the passageway 24, and has its front edge vertically disposed to bear against the inner face of the wall 13, and its rear edge inclined upwardly to bear against the adjacent end of the passageway, the smaller end of the said key being at the bottom, and provided with a transverse pin 26 to prevent its withdrawal from the passageway 19, the upper end of the wedge having an overhanging lip 27 to prevent the wedge from becoming disengaged with the bar 20 when the device is 105 not in use.

By driving the wedge downwardly, after the member 1 has been properly located against the side of the rail, the locking bar is drawn to the opposite rail of the track, and consequently the member 1 is tightly locked against the rail 9 and, if desired, the aforesaid spikes (not shown) may be applied to the notches 15 and driven into the ties 5 in the event of breakage to the 115 locking bar.

The member 1 is further provided with additional means for preventing any longitudinal movement of the same, in the shape of a pair of depending lugs 28 formed integrally with the rear wall 13 of the member and extending downwardly between the two adjacent ties 5 and, should the locking member or bar 20 fail to prevent the longitudinal movement of the member 1, one or the 125 other of said lugs 28 will contact with the side of the tie and effectually prevent any further movement of the replacer.

The other or "outside" member 2 is substantially of the same formation and struc- 130

ture as the member 1 and the same reference characters, in so far as they apply, have been used thereon, the locking means, method of attachment, strengthening ribs or webs, etc. 5 being precisely alike in each case, the only difference residing in the shape and contour of the upper surface of the member 2. In this member, the curved deflector 10 of the flange 8 is omitted, and the latter is extended straight across the highest point or apex 10 3, as indicated at 8^a, while the said apex 3 gradually falls toward the adjacent rail 9^a where it forms a rounded juncture with the upper end of a vertical wall 3^a at a point 15 above the tread of the rail, the said wall 3^a being, in effect, a continuation of the rail-butting wall 16 found in the first described member.

From the foregoing it will be seen that a 20 pair of car replacers has been provided, having all the advantages of the devices of the said Patent No.1294926, and some additional features in the form of improvements, which experience has proven to be 25 necessary, in order to bring the structure up to a standard of excellence and perfection.

What is claimed is:—

1. In a car replacer, a pair of members adapted to be placed alongside the inner 30 and outer rails of a railway track, each member comprising an elongated body portion having an upwardly inclined track surface or platform extending from each end to the transverse center thereof, the two 35 inclined surfaces meeting forming an apex, said track surface or platform decreasing in width from each end to the apex, and an up-standing wheel guiding flange extending from the outer corners of each end of the 40 body portion along said platform or surface toward the said apex and joining therat, said flange forming the outer wall of each platform or track surface, the flange on one

of said members having at the center an inwardly curved deflector which extends towards the adjacent rail, and the apex of the same member which inclines downwardly toward the rail having a longitudinal drop or fall extending alongside and below the ball or head of the rail, said drop or fall providing a longitudinally extending closure to receive the flange of the wheel and allow said flange to engage the inside of the head of the rail, the other member having its apex higher than the head of its rail and inclined 55 downwardly and inwardly and contacting with the inside of the head of the rail.

2. Car replacing means comprising a pair of similar members each composed of an elongated, hollow, metallic casting adapted 60 to be arranged along the rails of a track, one member being adjacent to the inner side of one of the rails and the other member adjacent to the outer side of the other rail, and each resting upon the ties and having 65 inclined portions on their bottom edges to receive the adjacent rail flange beneath the same and to rest thereon along that side adjacent to the rail, and a transverse locking bar slidably mounted in each member 70 and having one end passing beneath the rail and terminating in a hook to engage the opposite base flange thereof, said bar having an intermediate drop, the other end of the bar being elevated where passing through 75 the wall of the member and having a vertical slot therein, and a vertically sliding wedge or key adapted, when driven down, to draw the bar laterally and bind said hook around said rail flange and lock the respective member to the rail.

In testimony that I claim the foregoing as my own, I have hereto affixed my signature.

ALBERT N. LYBERGER.
